CUTOUT ATTACHMENT FOR ADVERTISING SIGNS

Don E. Williams, Kansas City, Mo., assignor to Butler Manufacturing Company, Kansas City, Mo., a corporation of Missouri

Filed Dec. 9, 1957, Ser. No. 701,604

5 Claims. (Cl. 40—125)

This invention relates primarily to outdoor advertising signs and deals more particularly with the construction and manner of assembly of cutout figures or panels so that they stand out in spaced relation from a fixed background, for example, the main copy area of an outdoor signboard.

One of the primary objects of the invention is to provide structure by which cutouts, as they are known in the industry, can be attached to a background in spaced relation thereto with a minimum of time and difficulty.

Another object of the invention is to provide support means for such cutouts which may readily be assembled with existing signs, and which, during shipment, take up little space. A feature of the invention in this respect lies in the provision of a special bracket and support arm in which the arm can readily be disassociated from the bracket without undoing bolts or screws, but yet in which the arm, while connected with the bracket, is firmly held against displacement from its normal extended position.

A further object of the invention is to provide a cutout mounting assembly wherein the installation of the cutout on the support arm can be accomplished by a simple downward vertical movement of the cutout relative the support arms once the cutout is preliminarily located in substantially its final position. A feature of my invention in this connection resides in the provision of means whereby the cutout need not be exactly centered relative the arms before dropping it into final position. This is of inestimable aid to the erection workers, particularly in situations where the cutouts are of unwieldy size or shape.

A further object of the invention is to provide a special support socket adapted to be secured to the back of the cutout in such numbers as required and which can be easily formed from a flat metal bar or strap.

Another object of the invention is to provide a cutout mounting assembly of the character described which is strong, rugged and capable of withstanding years of use.

Other and further objects of the invention together with the features of novelty appurtenant thereto will appear in the course of the following description.

In the accompanying drawings which form a part of the specification and are to be read in conjunction therewith, and in which like reference numerals indicate like parts in the various views;

Fig. 1 is a front elevation of a typical signboard fitted with a cutout supported according to the present invention;

Fig. 2 is a fragmentary perspective view of a portion of the copy area of the sign with the cutout removed and illustrating the support arms and attaching bracket;

Fig. 3 is a rear perspective view of the lower cutout element showing the support sockets attached thereto;

Fig. 4 is a sectional view taken along the line 4—4 of Fig. 1 in the direction of the arrows;

Fig. 5 is an enlarged sectional view taken along the line 5—5 of Fig. 4 in the direction of the arrows; and

2

Fig. 6 is a view taken along the line 6—6 of Fig. 5 in the direction of the arrows.

Referring to the drawings and initially to Figs. 1 and 4, the signboard I have selected for illustrating my invention is a typical one having a copy area made up of a plurality of rectangular panels 10 disposed in coplanar and side-by-side relationship. These panels are supported in any convenient fashion on horizontal stringers 11 (see Fig. 4) which extend from one end of the sign to the other. The stringers 11 may conveniently be angle irons to which are bolted or clamped the panels 10. The stringers are in turn supported by upright posts 12, any number of which may be spaced across the back of the sign. It will be understood that these posts are set in the ground or in concrete to provide a rigid footing. A decorative molding 13 is provided around the margin of the sign, this molding being supported from the posts and stringers. It will be understood that preferably the signboard is of the type wherein the panels are removable without disturbing the molding, stringers and posts.

Examples of signs for which the present invention is admirably suited will be found in Wishart Patent 2,775,833 issued January 1, 1957.

The cutout attachment illustrated herein to exemplify the invention comprises two separate elements, namely, an upper torso and head portion of a man indicated at 14, and a pair of keys 15. As is evident from Fig. 4, both these elements are supported in a forwardly spaced relation with respect to the plane of the signboard. The key cutout is supported at four points, indicated by reference numerals 16 in Fig. 1. The x's in this figure to which reference numeral 16 is applied denote nothing other than the locations of the support. It will be noted that these correspond with the locations of four support sockets 17 (later to be described) secured to the back of the key cutout 15 and shown in Fig. 3.

The support for the cutout is provided by a bracket and hanger arm assembly whose details may be best appreciated initially by reference to Fig. 2. The bracket in each case is indicated generally by reference numeral 18 and the hanger arm by 19.

Each bracket preferably comprises a flat base portion 18a adapted to lie against the face of a sign panel and be bolted thereto by bolts 20. At each end of this base portion there are outturned flanges, the lower one being indicated at 18b and the upper one at 18c. Forming a continuation of the upper flange 18c is a reversely bent and inclined extension 18d which terminates in a flat portion 18e bent to lie parallel with and in the same plane as the base portion 18a. This end lip or flange is likewise bolted to panel 10 by means of bolts 20.

The hanger arm 19 is a generally Z-shaped element having a vertical leg 19a, the horizontal leg 19b and an upturned outer end portion 19c. The vertical leg 19a of the hanger arm is received in suitable apertures 21 formed in the end flanges 18b and 18c of the bracket 18, as shown best in Fig. 6.

It will be noted that the inclined extension 18d is provided with an elongate slot 22 whose upper end 22a extends far enough toward the sign to provide an opening in line with the apertures 21 in the flanges 18b and 18c and whose lower end is closely adjacent the flange 18c. The hanger arm 19 is likewise received through this slot. In the position shown in Fig. 6, it is evident that the hanger arm is incapable of turning to one side or the other about the axis of the vertical portion 19a since the horizontal leg 19b is confined by the sides of the slot 22. However, it is free to be lifted from the hanger bracket if the occasion demands.

The upturned portion 19c of the hanger bracket provides the connecting link between the hanger arms and the sockets 17 on the rear of the cutouts and previously

adverted to. Referring particularly to Figs. 5 and 6 it will be noted that these sockets are formed of a strap of metal so bent that it is provided with two coplanar flanges 17a and 17b between which is located an outwardly bent or flared portion 17c. This outwardly flared portion is not in the form of a cylinder, but instead is a conical segment in which the lower end is of considerably greater diameter than the upper end. When attached to the back of the cutout the socket strap forms with the back of the cutout a socket opening which is of greater area at its bottom than at the top. The sockets 17 are located in the back of the cutout at points which correspond to the locations of the upturned portions 19c on the support arms.

In assembling the cutout with the support arms the procedure is first to place the cutout parallel with the sign with the lower ends of the sockets 17 above the upper ends 19c of the support arms. This can be accomplished by a crane if the cutout is of substantial size. The workers then steady the cutout so that the lower ends of the sockets are relatively centered with respect to the upstanding leg portions 19c, and the cutout is lowered thereon. The upwardly tapering conformation of the leg receiving portions of the sockets assist materially in completing installation quickly in that the sign need not be exactly centered with respect to the hanger arms in order that it be dropped into position. There is considerable tolerance provided by the tapered construction of the sockets, the only requirement being that the upper ends be brought into the lower ends of the sockets so that the socket may thereafter act as the guide to finally center the cutout on the hanger arms. The cutout is, of course, lowered until the lower edge of the socket strikes the extending horizontal portion 19b of the hanger arm and the cutout is now in final position. The weight of the cutout makes it unnecessary to supply any further bolts between the cutout and the arm or between the arm and the bracket. However, if a positive lock is desired, the hanger arm may be apertured transversely above and below the extremities of the socket and bracket as indicated at 19d, and cotter pins (not shown) inserted therein to form stops preventing lifting of the cutout from the arm and the arm from the bracket.

The upper cutout element 15, that is the head and shoulder portion of the man, is mounted to the sign in much the same fashion. However, as to the upper portions of the figure which lie above the signboard proper, special extension stringers 23 (see Fig. 4 and dotted lines in Fig. 1) are provided on the back of the signboard to extend well above the upper molding 13. These extensions may be secured to stringers 11 as shown in Fig. 4 by means of second angles 24. The brackets 18 in this case are mounted directly to the stringers 23 and the arms 19 (which have longer horizontal portions) are attached thereto in the manner previously described. The upper cutout is likewise provided with the sockets 17 at the places indicated in Fig. 1, and for every socket there is an arm and bracket. Installation of the upper element is accomplished exactly as in the case of the lower element although the upper element may be divided into sections if it proves too unwieldy.

It will be evident from the description which has preceded that should it ever become desirable to take down the cutout or to substitute a new cutout this can be accomplished with ease and facility. There are no bolts which need be removed. It is only necessary to lift the cutouts upwardly to disassociate the sockets from the hanger arms and free the cutout. The hanger arms can then be removed by lifting upwardly to disassociate them from their brackets. The brackets can then either be removed or the panels carrying them can be removed from the sign and clean panels installed.

The versatility afforded by the mounting system set forth herein is one of the most valuable features. For existing signboards the cutouts and mounting hardware,

that is the sockets, brackets and hanger arms, can be shipped with the hangers occupying but a fraction of the space they would otherwise occupy should the hangers be rigid with the brackets. Moreover, the hangers can be quickly installed in the brackets once the brackets are in place and no further bolting is required due to the unique holding arrangement provided by slot 22 in extension 18d.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. In an advertising sign of the type having an upright panel area presenting a vertical face, structure for detachably supporting cutouts of substantial area in spaced relation with said face comprising a plurality of bracket members secured to said face, each bracket having outwardly extending vertically spaced flanges and the flanges having vertically aligned apertures, a plurality of hanger members, one for each bracket, each hanger member having a vertical leg loosely received in said apertures, a horizontal leg at the upper end of the vertical leg and extending away from the sign, and an upright portion at the outer end of said horizontal leg, each bracket member including stop means above the uppermost flange and comprising members fixedly secured respectively to the face and to the last mentioned flange and engaging opposite sides of said horizontal leg to prevent turning of the hanger member about a vertical axis but permitting free upward movement of the hanger member sufficient to disengage the vertical leg from said apertures, and a plurality of downwardly opened sockets on the rear of said cutouts operable to slidably fit over said upright portions and connect said cutouts to said panel area in spaced relation with said face.

2. The combination of claim 1 wherein the sockets are each tapered so as to be of considerably greater area at the bottom opening than the cross-sectional area of the upright portion.

3. In an advertising sign of the type having an upright panel area presenting a vertical face, structure for detachably supporting cutouts of substantial area in spaced relation with said face comprising a plurality of bracket members, means for detachably securing said bracket members to said face at spaced locations thereon, each bracket member having a pair of outwardly extending vertically spaced flanges provided with vertically aligned apertures and a rearwardly and upwardly inclined extension from the outer end of the uppermost flange to adjacent the face of the panel, said extension on each bracket having formed therein an elongate slot having its long axis in a vertical plane normal to the plane of the face and one end thereof in line with the apertures in the flanges therebelow, a plurality of hanger members, one for each bracket, each hanger member having a vertical leg loosely extending through said apertures and a horizontal leg at the upper end of the vertical leg and extending away from said panel, said horizontal leg lying below said inclined extension for a portion of its length and emerging through said slot at a point remote from the axis of said apertures, said slot having a width only slightly greater than the thickness of said horizontal leg whereby the edges of said slot prevent rotation of said hanger away from its outwardly extending position, said horizontal leg terminating at its outer end in an upturned portion, and

a plurality of downwardly open sockets secured to the rear of said cutout and located to register with said upturned portions of said hanger members when the cutout is positioned parallel with said face, said sockets operable to fit slidably over said upturned portions and connect said cutout to said hangers in spaced relation with said face.

4. The invention as set forth in claim 3 wherein each said socket is tapered so as to present a downwardly open end of appreciably greater cross section than the cross section of the upturned portions of the hangers.

5. In an advertising sign of the type having an upright panel area presenting a vertical face, structure for detachably supporting cutouts of substantial area in spaced relation with said face comprising a plurality of bracket members, each bracket member having a flat base adjacent and abutting the face and terminating at its upper and lower ends in flanges extending away from the face, each bracket further having a reversely bent extension integral with the outer end of the uppermost flange and extending on an incline rearwardly and upwardly to a point adjacent the face, said extension terminating in a portion disposed parallel with and in abutment with said face, means for detachably securing said base and flat portions to said face, the flanges of each bracket having vertically aligned apertures and the reversely bent extension having an elongate slot with its long axis in a vertical plane normal to the face and the upper end of the slot aligned with the flange apertures therebelow, a plurality of hanger members, one for each bracket, each

5 hanger member having a vertical leg loosely extending through said apertures and a horizontal leg at the upper end of the vertical leg and extending away from said face, said horizontal leg lying below said inclined extension for a portion of its length and emerging through said slot at a point remote from the axis of said apertures, said slot having a width only slightly greater than the thickness of said horizontal leg whereby the edges of said slot prevent rotation of said hanger away from its outwardly extending position, said horizontal leg terminating at its outer end in an upturned portion, and downwardly open sockets secured to the rear of said cutout and located to register with said upturned portions of said hanger members when the cutout is positioned parallel with said face, said sockets operable to fit slidably over said upturned portions and connect said cutout to said hangers in spaced relation with said face.
